BY *Marion Jones*

ATTORNEYS

UNITED STATES PATENT OFFICE.

JOE EDGAR JONES, OF LOCKHART, TEXAS.

CASKET SUPPORT.

Application filed May 19, 1921. Serial No. 470,982.

To all whom it may concern:

Be it known that I, JOE EDGAR JONES, a citizen of the United States, and a resident of Lockhart, in the county of Caldwell and State of Texas, have invented certain new and useful Improvements in Casket Supports, of which the following is a specification.

This invention relates to casket supports, and more particularly to supports upon which a casket may rest when placed over a grave previous to the lowering thereof.

The object of the invention is to provide supports of the above character which are extensible and adapted for any width of grave.

It is also an object of the invention that the supports be each adapted to be closed into a compact unit for transportation or storage.

A further object of the invention is that the supports be so shaped that they will not have a tendency to roll when supporting a casket.

The invention is illustrated by way of example in the accompanying drawings, in which:

Figure 1 is a detail perspective view showing a casket of an infant's size being supported from a grave by supports which comprise the subject of the present invention.

Figure 2 is a side elevation of one of the supports when extended, the same being partly shown in cross section to more clearly illustrate the invention.

Figure 3 is a side elevation of one of the supports when shortened to its shortest length, and also being partly shown in cross section similar to Figure 2.

Figure 4 is a transverse section taken substantially on the lines 4—4 of Figure 3.

Figure 5 is a modified form of the invention.

Figure 6 is a view illustrating the use of the supports for carrying a casket to the grave.

Figure 7 is a view illustrating an adult's size casket when supported from a grave.

Referring to the drawings in detail, and particularly to Figures 1 to 4 inclusive, 10 indicates a casket of an infant's size which is being supported over the grave therefor as shown, by the means of a pair of supports generally indicated at 11, said supports resting upon the planks 12 as likewise shown.

The pair of supports 11 constitute the present invention, and since one is a duplicate of the other, only one will be described in detail.

Briefly, each support comprises a middle pipe section 13, the two intermediate pipe sections 14, which telescope the ends of the pipe section 13, and the two end pipe sections 15 which likewise telescope the outer end of the pipe sections 14. The outer surface of the pipe sections 15 are preferably hexagonal in shape as shown.

The middle section 13 carries at its one end a removable collar 16, said collar being secured in position by the set screw 17, Figure 3. The other end of the pipe 13 is likewise provided with a collar which is preferably formed therewith as indicated at 16'. Also the outer end of each intermediate pipe section 14 has formed therewith a collar 18 which is adapted to slidably fit within the outer sections 15. The inner end of each outer pipe section 15 and intermediate pipe section 14 has its passage restricted as at 19, the purpose of these restrictions being to form a stop for the collars carried on the ends of the intermediate pipe sections and the middle pipe section, and limit the extensible movement of the support as a whole.

Also these passage restrictions form a bearing for the pipe passing therethrough and cooperate with the collars on the outer ends of the pipes before mentioned, to form a rigid supporting structure. Also the outer end of each pipe section 15 is reduced as at 21, and said reduced portion formed with a thread to accommodate the cap 22.

Referring to Figure 6, the supports 11 are shown as being utilized for carrying the casket 23. This casket is of the adult size and the grave of a corresponding size. The supports have been extended and afford a convenient means for the pallbearers to support the casket and place the same over the grave. The pallbearers may grasp the reduced portion 21 and cap 22, as shown, and due to the extension of the supports from the sides of the casket the pallbearers are permitted to walk on each side of the grave in an erect manner and without approaching the edges of the grave too closely.

Referring to Figure 7, an adult's size casket is shown similar to that shown in Figure 6, and supported by the supports 11, over a grave as likewise shown. The supports have been extended to accommodate

the casket and the outer pipe sections 15 rest upon the framework about the grave. These pipe sections 15 having an outer surface hexagonal in shape prevent any rolling 5 of the supports upon the framework about the grave, and thus eliminate any danger in that respect.

Referring to Figure 5, the telescopic pipe sections 13, 14 and 15 constituting the extensible support are triangular in shape, as 10 shown. The outer sections 15 are also formed with a reduced portion over which there may be positioned a triangular shaped cap 25 and secured in position by the means 15 of a screw, as shown.

I claim:

1. An extensible support of the character described, comprising a middle section, a pair of intermediate tubular sections, each 20 telescoping an end of the middle section, a pair of outer tubular sections each telescoping an outer end of one of the intermediate sections, said outermost tubular sections each having an exterior surface consisting 25 of a plurality of flat surfaces extending longitudinally thereof, and stop means by which said sections are held from disengagement when the support is extended.

2. An extensible support of the character 30 described, comprising a middle tubular section, a pair of intermediate tubular sections each telescoping an end of said middle section, a pair of outer tubular sections each telescoping an outer end of one of the intermediate sections, a collar carried upon the 35 outer ends of each intermediate section and likewise upon both ends of the middle section, said collars each being adapted to fit within the interior of its associated tubular sections and one of the collars of the middle section being removable, a passage restriction formed at the inner end of each intermediate section and end section 40 adapted to slidably accommodate the pipe section passing therethrough and also adapted to limit the extensible movement of the support, and a cap threaded upon the outer end of each outer section.

45 tensible movement of the support.

3. An extensible support of the character described, comprising a middle tubular section, a pair of intermediate tubular sections each telescoping an end of said middle section, a pair of outer tubular sections each 50 telescoping an outer end of one of the intermediate sections, a collar carried upon the outer ends of each intermediate section and likewise upon both ends of the middle section, said collars each being adapted to fit within the interior of its 55 associated tubular sections and one of the collars of the middle section being removable, a passage restriction formed at the inner end of each intermediate section and end section adapted to slidably accommodate the pipe section passing therethrough, and also 60 adapted to limit the extensible movement of the support, and means whereby the sections may be disconnected from each other.

4. An extensible support of the character 65 described, comprising a middle tubular section, a pair of intermediate tubular sections each telescoping an end of said middle section, a pair of outer tubular sections each telescoping an outer end of one of the intermediate sections, a collar carried upon the 70 outer end of each intermediate section and likewise upon both ends of the middle section, said collars in each instance being adapted to slidably fit within the interior of its associated tubular sections and one of the collars of the middle section being removable, a passage restriction formed at the inner end of each intermediate section and end section 75 adapted to slidably accommodate the pipe section passing therethrough and also adapted to limit the extensible movement of the support, and a cap threaded upon the outer end of each outer section.

5. An extensible support of the character 80 described, comprising a plurality of telescopic tubular sections, and each outermost section having a plurality of exterior flat surfaces extending longitudinally thereof for the purpose described.

JOE EDGAR JONES.
